REPOINTER BAR AND METHOD OF
REPOINTING TEETHThomas Anthony Ratkowski, Chicago Heights,
Ill., assignor to American Brake Shoe Company,
New York, N. Y., a corporation of Delaware

Application June 17, 1947, Serial No. 755,110

2 Claims. (Cl. 76—101)

1

This invention relates to a repointer bar for use in renovating teeth for excavating implements and the like. More particularly, it relates to a repointer bar from which new points for worn teeth may be cut, which points will be of such construction as to retain their sharpness during the normal period of usefulness of the renovated tooth, and which have a high resistance to bending when in service.

The construction of the repointer bar which is the subject matter of the present invention is closely related to the construction of the dipper tooth disclosed in applicant's Patent No. 2,247,202, issued June 24, 1941.

The general idea of using a pre-formed repointer bar from which new points for worn dipper teeth may be cut is not new. However, no repointer bar has been developed which incorporates a structure which is designed to cause the points cut from this bar to retain their sharpness during their normal period of usefulness. Certainly it is as desirable to provide a new point for worn teeth which will maintain its sharpness as it is to provide a complete tooth which has that characteristic. As in the case of the teeth so designed, such construction in a new point for such teeth is of particular value in that the point does not become dull or blunt during its progressive wear. The renovated tooth thus has a maximum efficiency throughout the life of the new point.

Directly related to this ability to maintain their sharpness is the high resistance of these new points to bending. It is obvious that the efficiency of a tooth can be greatly impaired by a bending of the point. One of the important advantages of this new type of repointer bar is that the points which are cut from its have a construction which not only tends to cause the points to retain their sharpness but which also gives them strength enough to resist bending.

It is therefore the object of this invention to provide a repointer bar from which new points for worn teeth for excavating implements and the like may be readily cut.

It is a further object of this invention to provide a repointer bar which may be cut into new teeth points which are of such a construction as to retain their sharpness during their normal period of usefulness.

It is another object of this invention to provide a repointer bar from which new teeth points may be cut which are of such a construction as to not only retain their sharpness but also to resist bending when in service.

Still another object of this invention is to provide a novel repointer bar from which new points may be cut which are particularly adapted to being hard-surfaced after they have been secured to the tooth being renovated.

Further objects and advantages of this invention will become evident as the description proceeds, and from an examination of the accompanying drawing which illustrates one embodiment of the invention and in which similar numerals refer to similar parts throughout the several views.

In the drawings—

Fig. 1 is a fragmentary perspective view of a repointer bar embodying one form of this invention.

Fig. 2 is a view in longitudinal vertical cross section of an excavating implement tooth having a new point secured thereto, which point has been cut from the repointer bar shown in Fig. 1.

Fig. 3 is a view in transverse vertical cross section of the point shown in Fig. 2, the view being taken along the line 3—3 of Fig. 2.

Fig. 4 is a view in transverse vertical cross section of a point cut from a repointer bar embodying another form of the invention.

Fig. 5 is a fragmentary perspective view of a repointer bar embodying still another form of this invention.

Fig. 6 is a view in longitudinal vertical cross section of a point cut from the repointer bar shown in Fig. 5.

Fig. 7 is a view in transverse vertical cross section of the point shown in Fig. 6, the view being taken along the line 7—7 of Fig. 6.

Referring now to Figures 1 and 2 the repointer bar, indicated generally by the numeral 10, has a wedge-shaped cross section, with an apex 12 and two angularly disposed flat surfaces 14 and 16 forming the base of the wedge. A plurality of grooves 18 are laterally disposed in the surfaces 20 and 22 which form the sides of the wedge. These grooves 18 are, in turn, defined marginally in a lateral direction by the relatively narrow ribs 24.

The grooves 18, as shown in Fig. 1, extend from points adjacent the flat surfaces 14 and 16, and terminate at the apex 12 of the repointer bar.

As shown in Fig. 2, the bottom surfaces of the grooves 18 are curved inwardly toward the longitudinal axis of the repointer bar. The depth of the grooves at the apex 12 is such that the main body 26 of the repointer bar adjacent the apex 12 has a thickness substantially equal to the

width of that apex, the grooves gradually decreasing in depth as they extend toward the surfaces 20 and 22.

As shown in Fig. 2, when it is desired to renovate the worn excavating implement tooth 28, having the rounded forward end 30, a suitable section of repointer bar having a width equal to the width of the tooth is cut from the repointer bar. The point so cut from the bar is then properly aligned with the worn tooth 28 so that it forms an extension thereof adjacent the end 30 and is welded into place, as shown in Fig. 2, so that the welding material 34 fills in the V-shaped areas formed by the flat surfaces 14 and 16 and the end 30 of the tooth 28.

It is common practice when securing a new point to worn teeth to hard-surface the new point after it is welded to the tooth. The most generally used method of hard-surfacing it is to apply the surfacing material along the entire cutting edge of the new point, which would correspond to the apex 12 of the point shown in Fig. 2, and also to apply several beads or strips of surfacing material on each side of the renovated tooth at right angles to the cutting edge and extending from the cutting edge to the base of the tooth. As shown in Fig. 3, a new point cut from a repointer bar of the type shown in Fig. 1 lends itself readily to the hard-surfacing process. The grooves 18 are particularly adapted to receive hard-surfacing material, such as the material 36. If the new points are cut from the repointer bar along the longitudinal center line of the bases of the grooves 18, the lateral edges of the new point will have the L-shaped indentations 38 therein. These indentations 38 may also be filled with the hard-surfacing material 36, as shown in Fig. 3, so that the lateral edges are made more resistant to wear.

It has been found that the resistance to wear by the hard-surfacing in the grooves 18 does not start to function until the overall thickness of the point has been reduced, and a sharper cutting edge is therefore maintained for the remaining life of the point because of the presence of the hard-surfacing. In addition, the groove construction of the repointer bar provides a greater surface area in the points cut therefrom so that heat generated by the process of hard-facing is more readily dissipated than in the case of the repointer bars in common use today. This dissipation of heat results in a more satisfactory job of hard-surfacing so that the wear resistance of the new point is substantially improved.

An alternative form of the grooves which may be provided in the repointer bar is shown in Fig. 4. In this type of bar the grooves 40 on the two surfaces forming the sides of the wedge are not vertically aligned but are laterally displaced on one of the sides so that the grooves 40 and the ribs 42 are vertically aligned. This type of construction might be found desirable in cases where a greater resistance to bending is sought. As shown in Fig. 4, the hard-surfacing material 44 can be applied in the grooves 40 in the same fashion as previously described in connection with the form of repointer bar shown in Fig. 3.

The form of repointer bar shown in Fig. 5, which bar is designated generally by the numeral 46, has substantially the same cross-sectional shape as the repointer bar shown in Fig. 1. The grooves 48 are provided in the sides 50 and 52 of the repointer bar and are marginally defined in a lateral direction by the relatively narrow ribs 75

54. However, these grooves extend from points adjacent the angularly disposed flat surfaces 56 and 58 which form the base of the wedge and may be distinguished from the grooves 18 in the form of repointer bar shown in Fig. 1 in that they do not terminate at the apex 60 of the repointer bar but extend continuously around that apex from one side of the bar to the other, as shown in Fig. 6.

10 As shown in Fig. 7, hard-surfacing material 62 may be applied to the points cut from the type of bar shown in Fig. 5 in the grooves 48. Here again the hard-surfacing material may also be applied to the lateral edges of the new points if the 15 points are cut from the repointed bar along the bases of the grooves 48.

20 Although it is not shown in the drawing, obviously it would be possible to provide the repointer of the general form shown in Fig. 1 with ribs and 25 grooves of the same general shape as those shown in Fig. 7. No attempt has been made to illustrate all the various configurations which the ribs and grooves might be given since the mere existence of ribs and grooves, regardless of their 30 particular shape, is what is contemplated as being within the scope of this invention.

35 Although it has been stated above that the hard-surfacing material may be applied to the new points cut from a repointer bar embodying this invention, applicant does not wish to limit his invention to a repointer bar in which this hard-surfacing material has been incorporated, since its use may or may not be desirable depending upon the type of work in which the implement carrying the tooth is employed. Furthermore, if it is the primary desire of the user to obtain the benefits of the serrated or fluted construction of the points cut from such a repointer bar, it may not be desirable to employ the hard-surfacing 40 material at all. The operation of this fluted construction in teeth for excavating implements and the like has been carefully set out in the applicant's previously issued patent referred to above. The determination as to the desirability of employing hard-surfacing material as described will rest with the individual employing the repointer bar. It might even be desirable in some instances to place the hard-surfacing material on the ribs in the new points rather than in the grooves.

45 In any event, applicant has provided a novel 50 repointer bar for renovating teeth for excavating implements and the like, from which new points for worn teeth may be cut and which points have a construction which particularly adapts them to retain their sharpness and to greatly resist bending when in service.

55 The drawing and the above description are not intended to represent the only possible form of this invention, in regard to details of construction. Changes in form and in the proportion of parts, 60 as well as the substitution of equivalents are contemplated, as circumstances may suggest or render expedient, without departing from the spirit or scope of this invention.

65 What is claimed is:

1. An elongated bar of stock adapted to have relatively narrow transverse sections cut therefrom in the form of repointers for renovating teeth for use in excavating implements and the like comprising a bar having a substantially wedge-shaped transverse cross section, the side of said bar forming the base of said wedge-shaped cross section being divided along the longitudinal axis of said side into two angularly disposed faces, and the sides of said bar forming the wedge.

surfaces thereof having a plurality of converging transversely disposed grooves therein, said grooves extending along one of said wedge surfaces, across the apex of said bar and thence along the other of said wedge surfaces.

2. The process of repointing teeth for excavating implements and the like which comprises cutting a relatively narrow section of substantially the same width as one of said teeth from an elongated metallic bar of stock of substantially wedge-shaped transverse cross-section having a plurality of transverse grooves in at least one of the surfaces thereof, said section being cut so that at least each upper lateral edge of said section is substantially coincident with the longitudinal axis of one of said grooves, welding said section to said tooth so as to form a new point for said tooth, and subsequently depositing a hard-surfacing material in said grooves.
